STABILIZED NONIONIC SURFACTANTS IN SOLID FORMULATIONS CONTAINING ACTIVE CHLORINE COMPOUNDS

Jean Dupre, Levittown, Pa., assignor to Rohm and Haas Company, Philadelphia, Pa.
No Drawing. Filed July 17, 1967, Ser. No. 653,674
Int. Cl. C11d 7/56

U.S. Cl. 252—99

2 Claims

ABSTRACT OF THE DISCLOSURE

A solid built detergent formulation consisting of a low foaming nonionic surfactant containing a minor amount of an antioxidant, an active chlorine agent, and an alkaline builder, the antioxidant serving to stabilize the surfactant against degradation caused by the oxidative or other aggressive effects of the chlorine.

It has long been recognized that for many cleaning and sanitizing operations there are available three broad classes of highly effective materials: low foaming nonionic surfactants, active chlorine-releasing compounds, and alkaline builders. Each of these substances contributes usefully to the removal of soils. The alkaline builders are the primary detergents, and are responsible for effecting the removal of the bulk of most soils. The active chlorine compounds aid in the removal of stains and food films, and contribute sanitizing activity. In operations involving agitation of the detergent, such as spraying, pumping, or recirculating, the low foam nonionic inhibits the tendency of alkaline solutions of food salts to foam and improves the detergency and rinsing qualities of detergent solutions. Logically, it would appear that a combination of all three cleaning agents would provide the most satisfactory effect of all. But heretofore such a combination in a single granular dishwashing or other cleaning product has not been successfully attainable by means which are economically feasible.

A principal obstacle has been the incompatibility of the nonionic surfactant and the active chlorine compound. During storage a significant loss of the chlorine inevitably occurs and this results in a loss of cleaning, bleaching or sanitizing capacities. Upon storage the surfactant also tends toward a significant loss of performance such as by foaming excessively, a lessening of the ability to deform waters containing foam-causing substances, and overall loss in detergency. In fact, in some cases the degradation of the surfactants is so bad that a given surfactant cannot be used for its intended purpose.

The problem just described is not new to the art. It has been described and solved previously, albeit the solution was by means other than the present invention, an illustration being U.S. Pat. No. 3,306,858. That patent teaches the concept of incorporating an organic surface active agent with a solid carrier, coating the mixture with a substance that is impervious to chlorine attack during storage, and then combining the encapsulated material with a chlorine releasing agent. While such means are effective in providing adequate stability, the operation is difficult and much too costly to be economically feasible in most instances.

As pointed out in U.S. Pat. 3,306,858 the desire to combine organic surface active agents and chlorine releasing agents in a single product, along with alkaline builders, is that both classes of materials have certain highly useful properties in dishwashing and other detergent applications. The surface active agents function to

2

emulsify food soils, to inhibit foam caused by food soils, to promote wetting of dinnerware so as to eliminate or minimize spotting, and generally to improve the overall detergency of the composition for soil removal. The chlorine releasing agents improve detergency by their oxidizing action on food soils, particularly proteins, to convert them to a more soluble form. The active chlorine also serves to bleach out stains on dinnerware, as those caused by coffee or tea, and to minimize spotting on such ware by preventing build-up of soil films on their surfaces.

The obstacles to the effective combination of the surface active and chlorine-releasing agents include the fact that the preferred surfactants are organic nonionic polyether type materials which are readily susceptible to attack by active chlorine agents such as the hypochlorite ion. As a consequence of such reactions, the surfactants break down and in a relatively short period lose their desirable properties. The active chlorine content also is decreased as a result of the reaction with the surfactants so that by the time the detergent product is used by the ultimate consumer it frequently is substantially devoid of the desirable properties imparted by both the surfactant and the chlorine-releasing agents.

The present invention provides an improved, comparatively economical means for preparing detergent compositions suitable for dishwashing and similar applications in which organic nonionic surface active agents are compounded with chlorine releasing agents to form a suitable product which may be stored without undesired and significantly unacceptable reaction between these normally incompatible components. The present invention, moreover, provides detergent formulations of the type containing the otherwise noncompatible constituents as described previously, but which exhibit none of the aforementioned undesirable characteristics.

In essence, my invention consists in a modification of the surfactant which is combined with alkaline builders and chlorine-releasing agents, resulting in a product which thus consists of four main classes of materials instead of three as in the prior art. The modification consists of the addition to the surfactant of a minor amount of a composition which I call an antioxidant. The mechanism of the reaction by which the novel products of my invention are protected against chlorine attack, is not known with absolute certainty. However, because of the fact that the classes of compounds which I have found to stabilize nonionic surfactants against aggressive chlorine attack happen to have antioxidant properties, and a theoretical analysis of the causes of that stabilizing effect indicate an antioxidative action is taking place, I find it convenient to term the compositions in question "antioxidants."

In any event the observable net effect of the addition of one or more of these antioxidants to a nonionic surfactant is to reduce tremendously the chemical attack on the surfactant by active chlorine compounds in powdered alkaline formulations which occurs when no antioxidant is present. Moreover, this has been accomplished without adding to the loss of any of the active chlorine that is furnished by the chlorine releasing agent; in fact, in many instances the opposite result occurs for the amount of chlorine loss is reduced when compared with chlorine losses from formulations identical with the present invention except for the lack of the antioxidant. This in itself is as surprising as it is beneficial since antioxidants are materials which are themselves easily oxidized and thus would be expected to react with the chlorine releasing agents and thereby accelerate the chlorine loss. The four main classes of materials which are incorporated into the detergent formulation of the present invention have many sub-classes and components thereof

3

which may be utilized. For example, among the alkaline builders which may be employed (generally at levels of about 92 to about 98% by weight of the entire composition) in the present invention are di- and tri-sodium and potassium orthophosphates, alkaline condensed phosphate salts such as tetrasodium or tetrapotassium pyrophosphates, sodium tripolyphosphate, and sodium hexameta-phosphate, sodium and potassium hydroxides, sodium carbonate and bicarbonate, alkali metal borates, and alkali metal silicates. Both anhydrous and hydrated builders may be employed.

Among the many chlorine-releasing (or active chlorine) agents which can be utilized (generally at levels of about 1 to about 3 weight percent) in the present invention are sodium and potassium dichloroisocyanurate, di- and trichlorocyanuric acid, trichloro melamine, Chloramine T (sodium N-chloro-p-toluene-sulfonamide), dichlorodimethyl hydantoin, sodium, calcium and lithium hypochlorites, and the like. The chlorine-releasing agent can be combined with the alkaline builder, an example being chlorinate trisodium phosphate (which is a composition consisting of hydrated trisodium phosphate and sodium hypochlorite in intimate association in a crystalline form).

There are a great many classes of nonionic surface active agents which can be utilized (generally at levels of about 1 to about 5 weight percent), but all have one characteristic in common: they are all low foaming compositions. By this is meant they will all produce less than 3.0 cm. of foam when measured by the Hamilton-Beach test (described below and also in U.S. Pat. 3,021,372) under certain use conditions. Surfactants which produce more than that amount of foam, when so tested, are essentially useless in the practice of the present invention. Data showing the criticality of this foaming capacity, or "index," are set forth in Table I below.

Illustrative of the great variety of low foaming nonionic surface active agents which are useful in this invention are the following classes of compounds:

(1) Block copolymers of ethylene oxide and propylene oxide or butylene oxide (e.g., "Pluronics," the trade mark for products disclosed in U.S. Pat. 2,674,619 as compounds of the formula $\text{HO}-(\text{C}_2\text{H}_4\text{O})_x(\text{C}_3\text{H}_6\text{O})_y(\text{C}_2\text{H}_4\text{O})_x-\text{H}$, where y is at least 15, and $(\text{C}_2\text{H}_4\text{O})_{x+y}$ equals 10 to 90% of the total weight of the compound; "Product E-97," the trade designation for a polyoxyalkylene polymer having the formula:

where x , y and z are integers such that the average molecular weight of the compound ranges from 3600 to 4400).

(2) Polyethylene oxide and/or propylene oxide adducts of low molecular weight polyhydroxy or polyamine compounds. 60

(3) Terminated nonionics of the type

where R is alkoxy, alkyl phenoxy or alkyl amine of which the alkyl group contains 8-18 C atoms; R¹ is H or CH₃; R² is benzyl or a substituted benzyl, an alkyl chain of 1-8 C atoms, a halogen, a propylene oxide chain of 3 or more units, a lactam radical, or an alkyl acetal radical whose alkyl group consists of 1 to 8 C atoms; and x is 3 or higher.

-4

(4) Acetylenic diols of at least 7 C atoms, and their ethylene oxide adducts.

where R, R¹ and x are as indicated in No. 3 above, and A is either H or an alkyl group of 1 to 3 C atoms.

10 Variations within the foregoing classes of compounds
may occur and are fully within the purview of the present
invention. For instance, the amount of ethylene oxide in
a given compound will depend upon the alkyl chain length
15 or exact terminating group (e.g., benzyl, butyl, poly-
propylene oxide chain, etc.) employed. On the minimum
side it should be understood that sufficient units of ethylene
oxide must be incorporated in the surfactants to give them
desired surface active properties. As for the maximum
20 end of the range, the level of ethylene oxide units must
not exceed that which will cause the end product to foam
in excess of the 3.0 cm. limit described above as deter-
mined by the Hamilton-Beach test. Simple "go" and "no
25 go" tests will make selection of acceptable limits for the
ethylene oxide content in a given compound a relatively
routine procedure.

Among the antioxidants which can be utilized (generally at about 1 to about 10 weight percent based on weight of nonionic surfactant) in the present invention are substituted phenols, organic phosphites, amides, organic sulfur compounds, and aromatic amines. There are numerous classes of substituted phenols which may be employed. For example, one such class of compounds is represented by the formula:

in which R¹ to R⁵, inclusive, may each be OH, alkyl, alkoxy or alkyl amine. Another such class consists of alkylphenol-formaldehyde condensates. Specific examples of compositions encompassed by these classes are: di-t-butyl-p-cresol, 2,6 di-t-butyl 3 dimethylamino methyl phenol, p-t-octyl, dodecyl and butyl phenol-formaldehyde condensates, 1,2,3 trihydroxy benzene, 1,4 dihydroxy benzene, p-ethoxy phenol, etc. Still other such classes are known to the art, and some of them may be exemplified by the following compositions: 1,1,3 tris (2 methyl-4-hydroxy-5-t-butyl phenyl) butane and 3,3',5,5' (tetra-t-butyl) 4,4' dihydroxy biphenyl.

Some of the organic phosphites are encompassed by the formula

in which R', R" and R''' are alkyl, cycloalkyl, aryl, 65 alkoxyalkyl, aralkyl or tetrahydrofurfuryl, and X is oxygen or sulfur, and examples are trimethyl phosphite and thiophosphite, triethyl phosphite and thiophosphite, tributyl and triisobutyl phosphite, trissecondary and tertiary butyl phosphite, tributyl tri thiophosphite, tributyl 70 mono and dithiophosphite, trihexyl phosphite and trithiophosphite, tricyclohexyl phosphite and trithiophosphite, tri-2-ethylhexyl phosphite and trithiophosphite, triisooctyl phosphite, tridecyl phosphite and dithiophosphite, tri-lauryl phosphite and mono, di- and trithiophosphite, tri-octadecyl phosphite and trithiophosphite, triicosanyl, 75

phosphite, phenyl didecyl phosphite and trithiophosphite, phenyl dilauryl and distearyl phosphite, phenyl distearyl trithiophosphite, diphenyl decyl and lauryl phosphite, diphenyl stearyl phosphite and trithiophosphite, triphenyl phosphite, triphenyl mono-, di- and trithiophosphite, tri-*o*, *m*- and *p*-cresyl phosphite, tri-*p*-cresyl dithiophosphite, tri-*p*-octyl-phenyl trithiophosphite, tri-*p*-octylphenyl phosphite, triethoxyethyl phosphite, tributoxyethyl phosphite, tritetrabutylfuryl phosphite, tritetrabutylfuryl tri-thiophosphite, triphenyl ethyl phosphite, S-phenyldilauryl monothiophosphite, S-phenyl-didecyl monothiophosphite, S,S-diphenyl lauryl dithiophosphite, S,S-diphenyldecyl dithiophosphite, tri-*o*-naphthyl phosphite, tri-*o*-naphthyl phosphite, S,S-diphenyldecyl dithiophosphite, phenyldilauryl trithiophosphite, phenyldilauryl trithiophosphite, tri-*p*-dodecylphenyl phosphite, tri-*o*- and *m*-chlorophenyl phosphite, diphenyl lauryl trithiophosphite, S-lauryl diphenyl monothiophosphite, tri-*p*-chlorophenyl phosphite, tri-*p*-methoxyphenyl trithiophosphite, tri-*p*-methoxyphenyl phosphite, S,O-diphenyl-S-lauryl dithiophosphite, tri-*o*-methoxyphenyl dithiophosphite, S,O-dilaurylphenyl dithiophosphite. Other useful phosphite esters are cyclic phosphites, or pentaerythritol derivatives of one of the following formulae

and

where R' and R'' are as defined above and can be methyl, ethyl, propyl, butyl, isobutyl, secondary butyl, tertiary butyl, amyl, hexyl, heptyl, octyl, isoctyl, 2-ethylhexyl, decyl, isodecyl, lauryl, tetradecyl, cetyl, octadecyl (stearyl), eicosanyl, ethoxyethyl, butoxyethyl, methoxyethyl, tetrahydrofuryl, phenylethyl, aryl or haloaryl, e.g., phenyl, *o*-tolyl (*o*-cresyl), *m*-tolyl, *p*-tolyl, *o*-ethylphenyl, *p*-ethylphenyl, *p*-*t*-butylphenyl, *o*-*t*-butylphenyl, *m*-*t*-butylphenyl, *p*-octylphenyl, *p*-nonylphenyl, *p*-decylphenyl, *p*-dodecylphenyl, benzylphenyl, *o*-phenylphenyl, *p*-phenylphenyl, *o*-chlorophenyl, *m*-chlorophenyl, *p*-chlorophenyl, *o*-bromophenyl, *p*-fluorophenyl, *m*-iodophenyl, *o*-, *p*- and *m*-methoxyphenyl, *o*-naphthyl and *p*-naphthyl. In the formulae R₁, R₂, R₃, R₄, R₅, and R₆, are hydrogen or alkyl groups of 1 to 20 C atoms, and X is oxygen or sulfur. More examples of phosphites coming within the purview of the preceding formula may be found in U.S. Pat. 3,205,269.

Examples of the other classes of antioxidants are thiourea (amides), dilauryl thiodipropionate (organic sulfur compounds), and *o*-phenylene diamine (aromatic amines).

The choice of the antioxidants, surfactants, alkaline builders and chlorine releasing agents which should be selected for incorporation in a particular composition normally would be based upon a number of factors including odor, degree of discoloration, solubility, detergency, cost, etc. If desired, other additives may be incorporated as, for example, anti-tarnishing agents, anti-caking agents, perfumes, and agents to prevent removal of dinnerware overglaze (viz., sodium aluminates, boric acid, and aluminum acetate).

The data which are recorded in the tables below clearly exemplify the invention and illustrate its improvement over the prior art in terms of its stabilization of the surfactant against degradative attack by chlorine. The data in each instance were based upon tests run as follows. The antioxidants in each instance were dissolved in the nonionic surfactant at the desired level, generally at a 5% level based on the surfactant. The nonionic surfactants, which generally were present at 1 to 5% level in the detergent, were mixed with one or more of the alkaline builder ingredients which are present at levels of 92-98%. The solid chlorine-releasing agent was added last, at the 1-3% level, all the ingredients were mixed together preliminary to storage under various conditions, and this was followed by evaluation of the properties of the end products.

The storage conditions were of two types: (a) a highly accelerated test at 60° C. in sealed glass jars, and (b) a 14 day or 28 day test in flasks covered with a paper-polyethylene laminate, which permits the entry of water vapor, at 38° C. and 80% relative humidity.

As mentioned above, a critical requirement of the present invention is the use of a low foaming surface active agent. A comparison of widely divergent foaming values of different detergents is given in Table I. The measurement of the foam values recorded in that table and in the others which follow it was made by the Hamilton-Beach test method. According to that procedure, 0.72 gram of the detergent formulation was added to 200 ml. of water (0.36 weight percent detergent) in a test cell at 50° C., mixing with a Hamilton-Beach mixer for 3 minutes, then stopping the agitation and recording the foam height after 5 seconds. Food soil defoaming was measured using the same procedure except that increments of powdered milk (added as a 10% dispersion in water) are added after one minute periods of agitation. When the foam height exceeds 4.0 cm. (5 sec. value), the solution is no longer considered to be defoamed.

40

TABLE I

	Surface active agent	Foam height, cm.
45	CH ₃	
1	nC ₁₁ H ₂₂ O(CH ₂ CHO) ₂ (CH ₂ CH ₂ O) ₁₂ CH ₂ C ₆ H ₅	0.1
2	nC ₁₁ H ₂₂ O(CH ₂ CH ₂ O) ₁₀ -C(CH ₃) ₃	0.2
3	Pluronic L-62 ²	1.2
4	C ₁₇ H ₃₇ C ₆ H ₄ O(CH ₂ CH ₂ O) ₁₀ H	8.0
5	Sodium linear dodecyl benzene sulfonate	>12.0
6	Sodium lauryl sulfate	>12.0

¹ (1) All of the surface active agents are nonionics except Nos. 5 and 6 which are anionic. Only Nos. 1-3 are suitable; 4-6 definitely would be useless, particularly in high pressure machine applications of detergent solutions; (2) In these tests the surface active agent was present in the amount of 0.0075 weight percent, and the alkaline builder (30/25/41 sodium tripolyphosphate/sodium metasilicate anhydrous/sodium hydroxide) was present in the amount of 0.36 weight percent.

² A liquid condensate of polypropylene oxide and ethylene oxide wherein the polyoxypropylene group has a molecular weight of 1,501 to 1,800 and the condensate contains 20 to 30% by weight of ethylene oxide.

65 Table II, which follows, reflects experiments involving three different chlorine-releasing agents and three combinations of alkaline builders and two storage test conditions, some with and some without antioxidants. In the cases where no antioxidant was utilized there was a significant loss of performance (i.e. an objectionable increase in foam and a decrease in ability to defoam milk soil), and also a noticeable loss of active chlorine content. In the identical tests, except that 5% of an antioxidant was incorporated into the surfactant before preparing the formulation, the loss of defoaming ability of the surfactant was

reduced from 33 to 92% below the loss level obtained when no antioxidant was present.

TABLE II

Percent anti- oxidant ² added to surfactant ³	Formula- tion ⁴	Initial values		Stored		
		Foam	Percent milk defoamed	Foam	Percent loss of defoaming	Percent loss of active Cl
Test condition: ¹						
A	0 { C	{ 0.1	.47	3.0	96	25
	0 { D	{ 0.3	.46	0.4	4	5
	5 { D	{ 0.1	.55	1.1	73	27

	5 { E	{ -----	.60	-----	68	-----
			.61	-----	28	-----

¹ A=14 days at 38° C. and 80% relative humidity.

² B=3 days at 60° C. in sealed containers.

³ p-t-Octyl phenolformaldehyde condensate (low molecular weight polymer; molecular weight about 2,000).

⁴ C=2/30/25/41/2 surfactant/sodium tripolyphosphate/sodium metasilicate anhydrous/sodium hydroxide/potassium dichloroisocyanurate.

D=2/30/25/41/2 surfactant/sodium tripolyphosphate/sodium metasilicate anhydrous/sodium carbonate/potassium dichloroisocyanurate.

E=2/30/30/38 surfactant/sodium tripolyphosphate/sodium metasilicate pentahydrate/chlorinated trisodium phosphate.

Table III, which follows, contains data showing how sixteen different compounds representing five major types of antioxidants, significantly reduced the extent of loss of soil defoaming activity after storage in one formulation employing one specific surfactant and one specific chlorine releasing agent. At a level of 5% antioxidant in the surfactant all the antioxidants gave at least a 24% reduction in loss compared to the surfactant minus the antioxidant. A few examples illustrate the effect of increasing the amount of the antioxidant to 10% which was to further reduce the chlorine loss.

antioxidants along with examples of two antioxidants from Table III, but under different test conditions.

³ Foam before storage is 0.1-0.5 cm.

45

50

55

I claim:

1. The detergent composition consisting essentially of the following components:

(a) the alkaline builder ranges from about 92% to 60 about 98% by weight and is selected from the class consisting of di- and tri-sodium and potassium orthophosphates, alkaline condensed phosphate salts, sodium and potassium hydroxides, sodium carbonate and bicarbonate, alkali metal borates, and alkali metal silicates,

(b) the active chlorine agent ranges from about 1% to about 3% by weight and is selected from the class consisting of sodium and potassium dichloroisocyanurates, di and trichlorocyanuric acid, trichloro melamine, sodium N-chloro-p-toluene sulfonamide, dichlorodimethyl hydantoin, and sodium, calcium and lithium hypochlorites,

(c) the surface active agent ranges from about 1% to about 5% by weight and is selected from the class 75

10

consisting of the following groups of compounds:

(1) block copolymers of ethylene oxide and oxide or butylene oxide;

(2) polyethylene oxide and/or propylene oxide adducts of low molecular weight polyhydroxy or polyamine compounds;

(3) terminated nonionics of the type

where R is alkoxy, alkyl phenoxy or alkyl amine of which the alkyl group contains 8-18 C atoms; R¹ is H or CH₃; R² is benzyl, an alkyl chain of 1-8 C atoms, a halogen, a propylene oxide chain of 3 or more units, a lactam radical, or an alkyl acetal radical whose alkyl group consists of 1-8 C atoms; and x is 3 or larger;

(4) acetylenic diols of at least 7 C atoms, and their ethylene oxide adducts; and

(5)

where R, R' and x are as indicated in (3) above, and A is either H or an alkyl group of 1-3 C atoms; and

(d) the antioxidant is selected from the class consisting of substituted phenols selected from one of p-t-octyl phenolformaldehyde condensate, p-dodecyl phenol-formaldehyde condensate, p-t-butyl phenol-formaldehyde condensate, all said condensates having a molecular weight averaging about 2000; organic phosphites consisting of compounds having the formulae:

in which R', R'', R''' are alkyl, cycloalkyl, aryl, alkoxy alkyl, aralkyl or tetrahydrofurfuryl, and x is oxygen or sulfur, thiourea; and O-phenylene diamine.

2. The detergent composition consisting essentially of the following components:

(a) the alkaline builder ranges from about 92% to about 98% by weight and is selected from the class consisting of di- and tri-sodium and potassium orthophosphates, alkaline condensed phosphate salts, sodium and potassium hydroxides, sodium carbonate and bicarbonate, alkali metal borates, and alkali metal silicates;

(b) the active chlorine agent ranges from about 1% to about 3% by weight and is selected from the class consisting of sodium and potassium dichloroisocyanurates, di and trichlorocyanuric acid, trichloro melamine, sodium N-chloro-p-toluene sulfonamide, dichlorodimethyl hydantoin, and sodium, calcium and lithium hypochlorites;

(c) the surface active agent ranges from about 1% to about 5% by weight and is a terminated nonionic of the type

5

where R is alkoxy or alkyl phenoxy, of which the alkyl group contains 8-18 carbon atoms; R^1 is H or CH_3 ; R^2 is benzyl; and X is 3 or higher
(d) the antioxidant is one of p-t-octyl phenol formaldehyde condensate havin a molecular weight of about 10
2000, or triphenyl phosphite, or a mixture of the two.
